UNITED STATES PATENT OFFICE

ROGER D. DE WOLF, OF ROCHESTER, NEW YORK, ASSIGNOR TO COMBUSTION ENGINEERING CORPORATION, OF NEW YORK, N. Y., A CORPORATION OF NEW YORK

FUEL-HANDLING SYSTEM

Application filed August 1, 1925. Serial No. 47,419.

This invention relates to systems for handling fuel, and more particularly to that type of pneumatic conveying system, used in feeding pulverized fuel to furnaces, which is 5 known as the "closed system."

In practice, the coal introduced into the pulverizer carries with it more or less inherent moisture, as well as surface moisture, which, after a time, may be taken up or absorbed by the air in the system to such an extent that the pulverized coal will pack and tend to clog up the passages.

My invention, therefore, has as its primary object the provision of a fuel handling system wherein the water-content of the fuel-conveying air is limited to such a degree as to keep the system dry enough for efficient operation.

Another advantage of my invention resides 20 in the fact that the coal as delivered to the pulverizer need not be so carefully or thoroughly dried as heretofore since the drying of the system can be adjusted as necessary by a simple adjustment of certain valves provided for the purpose.

I aim also by my invention to utilize in an economical manner any and all air drawn from the return line of the system. The utilization of this air is of value for the reason 30 that it still carries a certain amount of coal dust after it leaves the separator.

How the foregoing advantages, and others which will no doubt occur to those skilled in the art, are obtained, will appear from the 35 following description, reference being had to the accompanying drawing which illustrates somewhat diagrammatically a boiler setting with a pulverized fuel handling system embodying my invention.

40 The features usual to such a system I have illustrated, and designate, as follows:

At the bottom is a mill or pulverizer 3 which receives fuel in lump form, or run-of-mine coal, through the conduit 2. The pulverized fuel is carried from the mill through 45 the pipe 4, to an exhauster 5, by which it is forced, in a stream of air, through the conduit 6 to a separator 7.

The fuel, separated from the carrying air, 50 is deposited in the bin 8 from where it may

be fed, as needed, by a suitable mechanism indicated at 9, through burner nozzles 10, into the furnace chamber, indicated as a whole by the reference numeral 11. The furnace has the usual boiler tubes 12 and drums 13, and 55 also a water-screen 14.

From the separator 7, a return-pipe 15 conducts the air, still bearing a certain quantity of fine coal dust, back to the pulverizer 3.

From the cycle of operations just 60 described, where the fuel-carrying air is continually passed back through the pulverizer in order not to waste what coal may remain in suspension in it, it is evident that unless the coal supplied to the pulverizer is very 65 thoroughly dried the carrying air in the system will soon be saturated with moisture from the coal.

The means I have provided for overcoming this difficulty consists essentially of two 70 conduits and certain valve controls for them, substantially as follows:

The conduit 16, with its fan 17, taps air from the return side 15, of the system and forces it into the combustion chamber at a 75 suitable point, for instance at the fuel-burner castings 10^a. A second conduit 18, draws heated air, either from the space between the walls of a hollow-wall furnace or, as here shown, from a point near the bottom 19, of the furnace, in which latter case the supply 80 of air drawn upon is usually that which enters by the ports 24, especially the lower ones. This heated air is admitted into the return line 15, that is, on the air-intake side 85 of the pulverizer 3. Valves 20, 21, 22 and 22^a are provided to regulate the amount of carrying air withdrawn from, and the amount of heated, or "make-up", air admitted to, the 90 system. The numeral 23 at the top of the return-pipe indicates a pressure-relief valve.

In some boiler settings it will be convenient or advantageous to employ, in addition to the discharging and replenishing conduits, 16 and 18, with their valves, a branch 95 pipe 25 with valve 26 to divert heated air directly from the conduit 18 to the primary air fan 17 when little or no air is being tapped from the return pipe 15.

The operation of the system is in this wise, 100

arrows indicating the direction of flow of the fuel and air streams:

The fuel admitted to the pulverizer 3, is sent by way of the conduits 4 and 6, through the medium of the fan 5, to the separator 7, and thence to the furnace 11, through the bin 8, feeders 9 and nozzles 10. The air from which the fuel is separated is returned through the pipe 15 to the pulverizer. By continual withdrawal of a certain amount of the air from this return line and a continual substitution of dry, heated, air, the dampness of the system can be readily controlled, and the rate of such substitution will be determined by the rate at which moisture is being introduced into the mill by the coal.

While the amount of moisture absorbed by the air in a "closed system", wherein the fuel-carrying air is continually passing back through the pulverizer, is sufficient to saturate this air in a comparatively short time, I have found that when a certain amount of "make-up" air is admitted to the system the rate of absorption of moisture in the air withdrawn from the system is not so high but that the withdrawn air can be economically utilized in the furnace itself. I take, therefore, the air which is withdrawn through the pipe 16, and which in practice always contains some fine coal dust, and admit it into the furnace where it is utilized in the combustion stream.

Assuming the moisture content of the coal to be high, and that the air absorbs considerable moisture therefrom, and as a result a considerable amount of air is to be drawn from the system; then valve 21 will be left open, valve 26 closed, and the primary air fan 17 will withdraw air from the return-line 15 through the medium of pipe 16. Heated air, sufficient to take the place of that discharged, will be drawn into the system through pipe 18, by the suction of the system created by the exhauster 5, valve 22^a being adjusted for this purpose. When the coal used has less moisture, valve 21 will not be opened so wide, and the fan 17 may then be partly supplied, either with room air drawn in through valve 20, or with heated air controlled by valve 26, or both, depending upon temperature conditions and rate of firing.

The temperature and dryness of the make-up air may be readily controlled by varying the positions of valves 22 and 22^a so as to admit any desired proportion of room air with the preheated air. Considerable room air must sometimes be admitted to prevent dangerous over-heating of the conveyor system.

When it is desired to operate the system without change of the carrying air, valves 21, 22 and 22^a will be closed and the fan 17 will draw all its air through valve 20, or else through conduit 25 with its valve 26, or both.

65 From the foregoing description of the op-

eration of my invention, it is apparent that efficiency of operation, economy of coal consumption and direct control of the humidity and temperature of the carrying air and of the air admitted to the burners are readily obtained.

I claim:

1. In combination with a furnace, a fuel handling system comprising a pulverizer and separator, conveying means from pulverizer to separator and a return air-pipe from separator to pulverizer, means for conveying fuel from the separator to the furnace, means for diverting air from the separator to a point of delivery to the furnace, and means adapted to deliver a preheated gaseous medium to said diverted air, or to the pulverizer or to both.

2. In combination with a furnace and an air fan therefor, a pneumatic conveying system including: a mill and separator, piping from mill to separator, a return line from separator to mill, means for conveying fuel from the separator to the furnace, a conduit for taking air from the return line to the fan, and piping adapted to deliver hot air from a region of furnace-heated air either to the fan or to the mill or both.

3. In combination with a furnace and its primary air fan, a pneumatic conveying system including: a mill and separator, delivery and return pipes between them, means for conveying fuel from the separator to the furnace, a conduit for taking return air from the system to the primary air fan, a hot-air pipe from a region of furnace-heated air to the air-intake side of the mill, and a branch pipe from said hot air pipe to the fan.

4. In combination with a furnace and its primary air fan, a pneumatic conveying system including: a mill and separator, delivery and return pipes between them, means for conveying fuel from the separator to the furnace, a conduit to supply air from the return side of the separator to the primary air fan, a second conduit from a region of furnace-heated air to the air-intake side of the mill; a shut-off valve in each conduit, a valve controlled port to the atmosphere in each conduit, and a valve-controlled by-pass from the region of heated air to the fan.

5. In combination, a pulverized fuel burning furnace, a closed circulatory fuel pulverizing and separating system therefor including a delivery line from pulverizer to separator and a return conduit from separator to pulverizer, means for conveying fuel from the separator to the furnace, means for supplying air heated by the furnace to the return conduit, and means for withdrawing air from said conduit and delivering it to said furnace.

6. In combination, a pulverized fuel burning furnace, a closed circulatory fuel pulverizing and separating system therefor including a delivery line from pulverizer to separa-

tor and a return conduit from separator to pulverizer, means for conveying fuel from the separator to the furnace, means for supplying air heated by the furnace to the return conduit, and means for withdrawing air from said conduit at a point between the separator and the point of entrance of the heated air thereto and for delivering it to the furnace.

In testimony whereof, I have hereunto
10 signed my name.

ROGER D. DE WOLF.
